Attorneys

UNITED STATES PATENT OFFICE.

TILDEN H. HARDMAN, OF COMMERCE, GEORGIA.

PLOWBEAM.

Application filed April 4, 1923. Serial No. 629,878.

To all whom it may concern:

Be it known that I, TILDEN H. HARDMAN, a citizen of the United States, residing at Commerce, in the county of Jackson and State of Georgia, have invented new and useful Improvements in Plowbeams, of which the following is a specification.

This invention generically appertains to plows, but it more especially comprehends an improved beam construction.

One object of this invention is to provide a plow and beam construction having means for adjusting the beam to relatively change the direction of the plow point to regulate the depth of the furrow.

Another object of this invention is to provide means governing the vertical adjustment of the beam capable of operation by the operator in his normal position at the plow handles.

A further object of this invention is the provision of an improved clevis structure attachable to the free end of the beam for holding the single or double tree and for regulating the side or lateral draft of the plow.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Figure 1 is a perspective view of a plow showing my improved beam construction and regulating means in operable position;

Figure 2 is a sectional view taken on the line 2—2 of Figure 1;

Figure 3 is a top plan view of the clevis, and

Figure 4 is a side elevation of the draft hook detached from the clevis.

Many efforts have been made in plow construction to effect regulation of the draft of the plow, that is, depth of the furrow, as well as the lateral draft or width of the furrow, and many types of beam and clevis construction have been employed to effect the above purposes. However, with more or less scant success, and it was to overcome the deficiencies of those now in use that I perfected the beam construction and novel adjusting means through the instru-

mentality of which the principal objects of the invention may be accomplished effectively and expeditiously by the operator while the plow or plows are in motion and without the necessity of the operator leaving his normal position.

In the illustrated embodiment characterizing this invention there is shown a stock or standard A with its lower extremities supporting the usual mold-board 5 and plow point 6 which may be of any standard construction, and also secured to the lower extremities of the stock A are the plow handles 7 which are braced and further secured to the said standard by suitable brace rods 8.

In the present instance, standard A is bifurcated at its upper end providing forwardly and parallelly extending arms 9 connected at their outer ends by the upstanding integrally formed U-shaped portion 10 forming a continuation of the said arms and together therewith constituting an auxiliary beam structure B. Slightly spaced from the point of bifurcation are the oppositely positioned upstanding ears 11 formed integrally with said arms 9 and centrally apertured, as at 12, for a purpose which will hereinafter more fully appear.

The beam 13 is adapted to extend through the U-shaped member 9, between the auxiliary beam members 10 and is suitably journaled to the upstanding supporting ears 11 in any well-known manner. Suitably secured to the top surface of beam 13 adjacent its inner end is the longitudinally extending T-shaped rail or track member 14, and adaptable for cooperation with the track 14 is provided the substantially wedge-shaped slidable block 15, said block having its flat or under surface longitudinally recessed as at 16, said recess conforming in configuration to the T-shaped portion of track 14, so that when the said block is mounted on the track, it may slidably travel the length of the track, and during its normal course is locked thereon against disengagement by the flanges of the track member. Also mounted on the upper surface of the beam 13 adjacent its inner end, is the perpendicular support 17 centrally apertured and internally threaded to receive the externally threaded rod 18, the inner end of said rod being loosely mounted in the end of block 15, as at 19, and having keyed 110

or otherwise secured to its free end hand-wheel 20, by means of which the regulator rod 18 is operated.

In order that the beam 13 may be held in its proper position at all times and prevented from sagging when the draft power is relieved, the block 15 is grooved on both sides spaced from its inclined face for cooperation with the inwardly projecting supporting lugs 21 integrally formed on the inner sides of the leg portion of the U-shaped member slightly spaced from the inner surface of the U.

Secured to the outer end of the beam 13 is the clevis structure C including the outwardly diverging arms 21 secured to the beam by bolts 22 or other suitable fastening means. The outer extremities of the said arms are apertured, as at 23, to receive the anchoring rod 24, which latter is retained in position by a threaded nut 25. Mounted on the anchoring rod 24, intermediate said arms, is positioned the horizontally notched end member 26. Clevis hook 27 is provided with an elongated aperture 28 and adapted to receive and to seat in the desired notch in the end piece 26. The outer or free end of the loop portion of the hook 27 is slotted, as at 29, to receive the catch or tongue 30 pivotally mounted therein, as at 31. The outer end of tongue 30 when in normal position is slightly spaced from the outer extremity of the slot and forms a seat for the spring 32, one end of which is adapted to seat against the projection 33 of the tongue 30 normally held diagonally across opening in the hook to prevent disengagement of the single tree, double tree, or other draft attaching means (not shown) when normally positioned in the hook.

The operation of the invention is as follows:

To regulate the lateral or side draft of the plow, it is only necessary to tilt upwardly the hook 27 until the notched edge of the member 26 is in longitudinal alignment with the apex of the opening 28 whereupon the said hook may be positioned in any desired notch of the said member 26 and any desired width of the furrow may thereby be obtained. To regulate the depth of the furrow it is but necessary for the operator to rotate rod 18 which moves block 15 along track 14, and when said block is moved outwardly the plow point 6 is directed downwardly and the plowing depth thereby increased, and when the block is

drawn rearwardly the plow point is directed upwardly and hence the depth of the furrow decreased.

It will be observed that I have designed a beam and clevis regulating structure admitting of a wide range of adjustment, simple in construction, efficient for the purposes intended, economical to manufacture, and easily operated.

In practice, I have found the form of my invention illustrated in the accompanying drawings and referred to in the above description, as the preferred embodiment, is the most efficient and practical; yet realizing the conditions concurrent with the adoption of my device will necessarily vary, I desire to emphasize that various minor changes in details of construction, proportion and arrangement of parts, may be resorted to within the scope of the appended claims without departing from or sacrificing any of the principles of this invention.

Having thus described my invention, and without enumerating variations and equivalents, what I desire protected by Letters Patent is as set forth in the following claims:

1. A plow, including a standard embodying an auxiliary beam, a main beam coacting with the auxiliary beam and pivoted to the standard, a track mounted on the beam, a block slideable on the track, screw means mounted on one end of the beam for moving the block on the track, inwardly projecting lugs carried by the auxiliary beam engageable in slots carried by the said block for holding the said beam in any desired position in its vertical adjustment, and means carried by the free end of the beam to effect its sidewise or lateral adjustment.

2. A plow, including a standard, a beam pivoted to the standard, said standard being apertured to receive said beam, a track mounted on the beam, a block adapted for interlocking and slideable engagement with said track, screw means mounted on one end of the beam for moving the block on the track, inwardly projecting lugs carried by the auxiliary beam engageable in slots carried by the said block for holding the said beam in any desired position in its vertical adjustment, and means carried by the free end of the beam to effect its sidewise or lateral adjustment.

TILDEN H. HARDMAN.
